UNITED STATES PATENT OFFICE.

JOHN F. KIRGAN, OF PHILLIPSBURG, NEW JERSEY, ASSIGNOR TO INGERSOLL-RAND COMPANY, OF JERSEY CITY, NEW JERSEY, A CORPORATION OF NEW JERSEY.

MULTIPLE-EFFECT EVAPORATING APPARATUS.

Application filed July 12, 1923. Serial No. 651,025.

To all whom it may concern:

Be it known that I, JOHN F. KIRGAN, a citizen of the United States, and a resident of Phillipsburg, county of Warren, and 5 State of New Jersey, have invented a certain Multiple-Effect Evaporating Apparatus, of which the following is a specification, accompanied by drawings.

This invention relates to evaporating apparatus, but more particularly to multiple effect apparatus, suitable for use in the sugar industry in evaporating sugar syrup, but also applicable to the evaporating of other liquids, as desired.

10 15 The object of the invention is to enable multiple effect evaporating apparatus to be more economically used with a main condenser, and with an intercooler or inter-condenser connected to the main condenser 20 and also to two stage evacuating apparatus.

By venting the steam box of the last or final effect of the evaporating apparatus to a separate two stage vacuum producing apparatus, independent of the main condenser 25 and intercooler, the primary steam jets of the evacuator for the main condenser, and the main condenser itself, are relieved of this air and vapor leakage, so that a smaller vacuum pump may be used for evacuation.

30 35 In the copending application of Paul A. Bancel, Serial No. 644,130, filed June 8, 1923, to which I am permitted to refer, the steam box of the last or final effect of the evaporating apparatus is vented directly to the intercooler or inter-condenser, which is connected to the main condenser, but it has been found that in some instances the preferable arrangement is to vent the steam box of the last effect to a separate and independent two stage vacuum pump, in which a 40 still lower vacuum may be economically maintained than required for the intercooler, but appreciably higher than the steam pressure in the last or final effect of 45 the series of evaporators.

The invention is shown in one of its preferred forms in the accompanying drawings, in which the figure is a diagrammatic side elevation of a multiple effect evaporating 50 apparatus embodying the invention.

Referring to the drawings, a plurality of steam heated evaporators A are connected in series with each other, by connecting the steam and vapor outlet pipe B of each 55 evaporator or effect, to the steam inlet C

of the steam box G of the next adjacent evaporator or effect. Steam for heating purposes is supplied at the steam inlet D of the first evaporator from any suitable source, (not shown), and a main condenser, in this instance a barometric condenser E is connected to the steam outlet pipe F of the last effect. The evaporators A are of any suitable or standard construction, in which the syrup is heated in the lower tank portions forming liquid containing compartments or chambers, and the sugar is withdrawn from these chambers at the bottom outlets H. The main discharge outlets from the steam boxes G may be connected in any suitable manner (not shown) to evacuating apparatus.

The barometric condenser E may be of standard construction. An intercooler J which may be like that disclosed in U. S. Patent No. 1,526,040, granted to Paul A. Bancel, February 10, 1925, for steam jet vacuum pump is connected to the main condenser by the pipe K and primary augmentor jets L supplied with steam from the supply pipe O compress air and gases from the main condenser and discharge into the intercooler at low vacuum. The intercooler is supplied with water by the pipe P connected to the water supply pipe Q of the main condenser. A vacuum pump S connected to the intercooler by the pipe T forms the second stage of the evacuating apparatus.

In accordance with this invention, auxiliary steam-box vents W for the purpose of venting non condensable gases are connected to a two stage evacuating apparatus or pump R, separate and independent from the main condenser E and intercooler J. The pump R is provided with the primary jet or jets U and the secondary jet or jets V, supplied with steam in any suitable manner. The jet U may have a steam connection b and the jet V may have a steam connection a. Condensing water may be supplied to the evacuating apparatus or pump R by means of the pipe a from any suitable source, as for instance, from the inlet pipe Q of the main condenser, and the water outlet from the pump R may conveniently be connected with the main stand pipe of the main condenser. In the present instance, the auxiliary vents W are located at the lower portions of the evaporators A in the 100 105 110

steam belts or boxes G, and the pipes X from the vents W are connected to the common auxiliary vent pipe Y which is connected to the independent two stage 5 evacuator R. In such construction, the primary jet or jets U are interposed in the common vent pipe line Y.

I claim:

Multiple effect evaporating apparatus, 10 comprising a plurality of steam heated evaporators connected in series and having steam boxes, in combination with a main condenser for said series of evaporators having an intercooler connected thereto, main 15 evacuating apparatus connected to said intercooler, a two-stage evacuator separate

and independent from both the main condenser and intercooler, and capable of producing a vacuum appreciably higher than the steam pressure in the final effect of the 20 series, and means for venting non-condensable gases from the steam box of the said last effect into the said independent two-stage evacuating apparatus, thereby causing a flow of air and non-condensable gases or 25 vapors from the steam box of the said last effect into the said independent evacuating apparatus.

In testimony whereof I have signed this specification.

JOHN F. KIRGAN
